UNITED STATES PATENT OFFICE.

EDWIN M. ROSENBLUTH, OF PHILADELPHIA, PENNSYLVANIA.

DESIGN FOR A LAMP-BODY.

No. 38,133.

Specification for Design.

Patented July 24, 1906.

Application filed March 3, 1904. Serial No. 196,459. Term of patent 7 years.

To all whom it may concern.

Be it known that I, EDWIN M. ROSENBLUTH, of Philadelphia, in the State of Pennsylvania, have invented a new, original, and ornamental Design for a Lamp-Body, whereof the following is a specification, reference being had to the accompanying drawings.

In the drawings, Figure I is a perspective view of a lamp-body, showing my new design. Fig. II is a side elevation of said lamp-body.

I claim—

The ornamental design for a lamp-body as shown.

EDWIN M. ROSENBLUTH.
